COMBINATION FENCE TOOL

Carl A. Hadland, Plainview, Minn.

Application July 19, 1937, Serial No. 154,378

3 Claims. (Cl. 140—123.5)

This invention relates to a combination fence tool, more particularly a substantially S-shaped metal bar adaptable for numerous uses including uses as a crow-bar, a wrecking bar, a claw bar and nail puller, a wire stretcher and tightener and wire splicer.

Important objects of my invention are the provision of a combination metal tool of substantially S shape, having at one end a rounded, beveled bifurcated claw usable as a nail puller or as a crow-bar; having an intermediate integral right-angled portion with a tongue thereon, and having a turned-back opposite end terminating in a pick or point.

15 A further object of my invention is the provision of a combination tool in substantially the form of an S-shaped crow-bar having a straight intermediate portion and right-angled end sections integral with said intermediate portion, the extreme ends being formed as a pointed bit and bifurcated claw respectively.

20 A further object of my invention is the provision of the aforesaid combination tool having a spaced apart tongue secured on and parallel to its shank or intermediate portion providing means for gripping and stretching a barbed wire, and also having a hole through said intermediate portion adapted to receive splicing wire or the like and whereby said tool is rotated as a crank 25 to draw two or more wires together.

25 Other and further objects of the invention will be apparent from the following specification, description and claims.

This invention (in a preferred form) is illustrated and described in the following specification.

On the drawings:

Fig. 1 is a perspective view of my combination tool in typical wire stretching position against a post.

Fig. 2 is an enlarged fragmentary view taken on line 2—2 of Fig. 1.

Fig. 3 is a perspective view of my combination tool in the initial position for splicing and drawing together two spaced apart wires.

Fig. 4 is a perspective view of the same after several rotations of the tool from the position of Fig. 3.

Fig. 5 is a view of spliced wire sections after the completion of the operations shown in Figs. 3 and 4.

Reference numeral 10 designates the intermediate straight portion of the metal bar, with right-angled integral sections 10a and 10b extending perpendicularly from the opposite ends

thereof. As indicated in the drawings, portion or bar section 10b terminates in a bifurcated claw 11 which is preferably formed by flattening and widening said end by forging or the like and thence bending the same slightly to form a curved surface 11a. Said claw or bifurcated end is usable as a nail puller, for ripping, prying and like uses.

The opposite end of bar section 10a terminates in a perpendicularly extending pick, pike, point, bit or hook 12 which is turned back to a position substantially parallel with intermediate section 10, and which point has many well known uses such as ripping, prying, etc., including especially the pulling of staples. All the portions or sections 10, 10a, 10b, 11 and 12 lie substantially in the same place.

The intermediate portion of my combination tool is provided with a metal tongue 13 which may be either welded to or formed integrally with the intermediate section 10a and longitudinally and on the side thereof. Said tongue has its end offset and designated by numeral 14 so that said tongue end 14 is spaced apart from the bar section 10a and positioned a short distance from the right-angled bend forming the juncture of sections 10 and 10a.

As clearly illustrated in Figs. 1 and 2, the bar tool is in a horizontal plane and against a post 15, a barbed wire 16 being engaged by projecting end 14 of tongue 13, and the section 10a being braced against the post 15. When it is desired to engage a barbed wire, the tool is moved to insert the barbed wire behind tongue end 14, and thence bracing the tool against the post and thereby stretching the wire to the desired degree, whereupon the user may brace his body against the bar tool wherein the bent end 10b rests against the hip and the user thence has both hands free to position and drive staples to hold the wire on the post.

An important feature of my invention is the wire splicing means which comprises the afore-described bar tool having an aperture 17 extending through section or portion 10a thereof as shown in the drawings.

When it is desired to repair and splice two ends of a barbed wire, which are usually separated apart when broken by the tension thereof, a short piece of smooth wire 18 is doubled and loop 18a formed through loop 19a of wire 19 as shown in Fig. 3, and both the free ends 18b and 18c of wire 18 are passed through loop 20a of wire 20 which is formed on the other wire to be joined. Thence one of the free ends of splicing wire 18 is inserted through aperture 17 of bar tool 10 and said bar

tool rotated as a crank to define a substantially vertical plane. This will cause the splicing wire 18 to be drawn through loop 20a to draw the loop 20a and 19a closer together, one end of splicing wire being wound about the bar section 10a as shown in Fig. 4. When the two wires have been drawn together to the desired degree the free end 18b is bent back and twisted about the loops 18a and 19a and thereupon the tool will be rotated in reverse direction to unwind the coiled portion of splicing wire 18; the tool then is removed by withdrawing said wire from aperture 17. Then the end 18c is bent back and wound and twisted about the splicing wire 18, about the loop 20a if desired or about loop 18a and 19a to securely hold the respective wires in tight and spliced position, such as illustrated in Fig. 5.

Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim as my invention:

1. In a combination tool, a substantially S-shaped bar having one end curved and bent angularly and providing handle gripping means, and having its opposite end bent to form an angular hook, an offset tongue on the side of said bar

forming a deep longitudinally extending recess therewith adapted to engage a barbed wire or the like, the intermediate portion of the bar having an aperture therethrough adapted to receive a splicing wire and permitting rotation of such wire to draw separated wire ends together.

2. A combination tool of substantially S-shape, comprising integral end sections extending in substantially opposite directions connected by an integral intermediate shank portion, one of said end sections having a transverse aperture therein, an angularly extending integral hook on the end of one of said end sections, said aperture being adapted to receive a splicing wire for connecting together a pair of spaced apart wires or the end of a wire being stretched, and a gripping tongue on said shank portion adapted to engage a barb wire or the like when stretching the same.

3. A combination tool of substantially S-shape, comprising integral end sections extending in substantially opposite directions connected by an integral intermediate shank portion, and an offset hook-like tongue secured longitudinally of and on the side of said intermediate shank portion and forming a wire-gripping member therewith, one of said sections providing a gripping member for rotating said tool and adapted, when rotated, to wind a wire gripped by said hook-like tongue to draw same to means on which said tool is supported.

CARL A. HADLAND.
